UNITED STATES PATENT OFFICE.

JOSEPH A. COYLE AND WELLESLEY B. COOPER, OF AMSTERDAM, NEW YORK, ASSIGNEES TO STEPHEN SANFORD & SONS, INC., OF AMSTERDAM, NEW YORK, A CORPORATION OF NEW YORK.

LOOM TUBE FRAME AND SPOOL.

Application filed June 23, 1927. Serial No. 200,957.

The present invention relates to looms and more particularly to the type in which the yarn is carried by spools mounted on tube frames which are carried by an endless feeding mechanism to present the spools consecutively to the loom. An object of this invention is to make it possible to use a spool which is substantially the length of the tube frame notwithstanding the width of the material being woven. Another object of the invention is to provide a connection between the tube frame and the spool intermediate of the ends of the latter in order to permit the use of a single long spool with wide loom tube frames without any danger of the sagging of the spool between its ends. Still another object of the invention is to provide a yarn spool with an intermediate support on a tube frame.

To these and other ends, the invention consists of certain parts and combinations of parts all of which will be hereinafter described: the novel features being pointed out in the appended claims.

In the drawings:

Fig. 1 is a plan view of a spool constructed in accordance with this invention;

Fig. 2 is a fragmentary view of one end of the spool and the tube frame showing parts in section;

Fig. 3 is a fragmentary view of the sag preventing connection between the yarn spool and the tube frame;

Fig. 4 is a fragmentary view of the right hand end of the spool and the tube frame;

Fig. 5 is a fragmentary sectional view showing the manner in which a flange on the spool bears on the tube frame; and

Fig. 6 is a fragmentary view showing the sag connection between the tube frame and spool.

In looms and particularly those of the type designed for weaving Axminster rugs and other pile fabrics, it is customary to mount the yarn which forms the pile upon spools supported on tube frames which are presented to the loom consecutively by an endless carrier. Heretofore, when the material being woven has been of considerable width as in wide rugs, each tube frame has supported thereon a plurality of axially aligned spools extending across the entire width of the material being woven. The use of a plurality of spools for a single wide tube

frame has heretofore been considered necessary as the weight of the material would heretofore produce a sagging condition in a single long spool due to the weight of the yarn and the pull of the yarn in weaving. This would cause an undesirable condition in the weaving operation.

According to this invention, it is possible to use a single long spool for each tube frame notwithstanding the width of the material being woven as this sagging condition is entirely eliminated.

In the illustrated embodiment of the invention, 1 indicates the tube frame having the tubes 2 projecting therefrom. This tube frame has at opposite ends bearings 3 in which the bearings 4 projecting from opposite ends of the spool turn.

The spool is substantially coextensive in length with the tube frame and comprises, in this instance, a tubular metallic spindle 75 portion 5 into the ends of which the plugs 6 of wood or other material are fitted. On opposite ends of the tube 5 are fitted the flanges 7 made from sheet metal and pressed to provide a central tubular portion 8 fitting 80 the exterior of the tube 5 and a surrounding periphery 9 which may be engaged by a spring brake finger 10 supported by the tube frame 1.

The sag prevention connection between the tube frame and the spool, in this instance, is arranged between the ends of the spool and comprises preferably a surrounding flange 11 on the tubular portion 5 substantially midway between the end flanges 7. 90 This flange has a cylindrical outer surface 12 forming a bearing or shoulder for cooperating with a bearing on the tube frame 1. In this instance, the bearing on the tube frame comprises a housing 13 having its upper surface conforming to the surface of the cylindrical surface 12 and provided with roller bearings 14 to reduce the friction between the two bearings. This cooperation between the rollers 14 and the surface 12 100 prevents the sagging of the spool toward the tube frame when the spool and the tube frame are situated on the underside of the endless carrier.

As the endless carrier moves the spool and the tube frame upwardly and the spool becomes positioned below the tube frame there is a tendency for the spool to sag away from

the tube frame and in order to prevent this sagging action a novel provision is made in the connecting means. In this instance, the 5 flange at the center of the spool has an inner annular shoulder. For cooperating with the shoulder there is provided a finger 16 pivoted at 17 to the tube frame 1 beneath a plate 18 which is secured on the rear side of the tube frame. Associated with this finger 10 is another finger 19 also pivoted at 16 but curved in a direction opposite to the finger 16 to cooperate with that face of the flange 11 opposite the face engaged by the finger 16. A spring 20 connected to both of the 15 fingers 16 and 19 holds said fingers toward each other on opposite sides of the central flange. The engagement of the finger 16 with the surface 15 effectively holds the flange 11 to the bearing rollers 13 in any position to which the tube frame and its 20 spools may be shifted by the endless tube frame carrier of the loom.

With the end in view of permitting the ready detachment of the spool from the tube frame, a means is provided for effecting the 25 separation of the fingers 16 and 19. This means, in this instance, comprises a plunger 21 guided in a bearing 22 and having a headed end 23 adapted to cooperate with 30 extensions 24 and 25 provided respectively on the fingers 16 and 19. A pressure on this plunger 21 inwardly causes the head 23 to bear on the extensions 24 and 25 and move the fingers 16 and 19 away from each other 35 against the action of the spring, so that the flange 11 may be disengaged from the bearing rollers 14 and disconnected from the yarn spool.

From the foregoing it will be seen that 40 there has been provided a loom in which a single spool substantially coextensive in length with a wide tube frame may be employed without any sagging action therein, thus doing away with the provision of a plurality of spools upon a single tube frame 45 when a fabric of considerable width is being woven. A support is provided for the spool at a point between its ends and upon the tube frame. In this instance, this support embodies a flange or side on the spool frame 50 cooperating with a bearing on the tube frame. This flange holds the spool against sagging toward the tube frame and sagging away from the tube frame is prevented by 55 devices which are mounted on the tube frame and cooperate with the flange on the spool to hold the flange in cooperation with the bearing on the tube frame when the spool is arranged below the tube frame. It is 60 evident that the structure as a whole provides connection between the tube frame and the spool intermediate the ends of the spool for preventing the sagging of the spool between its ends.

65 It is customary when the tube frame is

"wiping in" or feeding the yarn to the fabric being woven to support the tube frame at its center by a movable finger on the loom. This movable finger may be employed for co-operating with the plunger 21 in order to 70 press the same inwardly against the action of the spring 20, so as to separate the holding fingers 16 and 19, whereby when the yarn is being fed from the spool, the flange 12 will be free to rotate on the warp beam. 75

What we claim as our invention and desire to secure by Letters Patent is:

1. The combination with a tube frame, of a yarn spool supported at opposite ends on the tube frame, and cooperating means, part 80 of which is on the spool intermediate the ends of the latter, and part of which is suitable arranged to cooperate with the spool part for holding the spool against sagging between its ends relatively to the frame when the latter is in wiping in position.

2. The combination with a tube frame, of a yarn spool supported at opposite ends on the tube frame, and means providing a support on the tube frame for an intermediate 90 portion of the spool.

3. The combination with a tube frame, of a yarn spool supported at opposite ends on the tube frame and means providing a support on the tube frame for an intermediate 95 portion of the spool, said means embodying a part on the spool rotatably supported on the frame.

4. The combination with a tube frame, of a yarn spool supported at opposite ends on the tube frame, and means providing a support on the tube frame for an intermediate 100 portion of the spool, said means embodying a circular flange on the spool and a bearing on the tube frame on which the flange turns. 105

5. The combination with a tube frame, of a yarn spool supported at opposite ends on the tube frame, and means providing a support on the tube frame for an intermediate 110 portion of the spool, said means embodying a circular flange on the spool and a bearing on the tube frame on which the flange turns, the flange having an annular shoulder on a side thereof, and means carried by the tube frame for engaging said shoulder to hold the spool against movement away from the tube. 115

6. The combination with a tube frame, of a yarn spool supported at opposite ends of the frame, and a sag preventing connection 12 between the frame and a portion of the spool between the ends of the latter having provision for permitting the rotation of the spool on the frame.

7. The combination with a tube frame, of a yarn spool supported at opposite ends on the frame, and a sag preventing connection 12 between the frame and a portion of the spool between the ends of the latter having provision for permitting the rotation of the 11

spool on the frame, said connection embodying two circular surfaces on the spool, disposed in opposite directions, and two means on the frame engaging said surfaces, one holding the spool against sagging toward the frame and the other holding the spool against sagging away from the frame.

8. The combination with a tube frame, of a yarn spool supported at opposite ends on the frame, a flange surrounding the spool between the ends thereof, and means carried by the frame and interlocking with the flange to hold the spool against sagging.

9. The combination with a tube frame, of a yarn spool supported at opposite ends on the frame, a flange surrounding the spool between the ends thereof, and means carried by the frame and interlocking with the flange to hold the spool against sagging, said means having a movable portion to permit the interlocking connection to be destroyed in order that the spool may be separated from the frame.

10. A yarn spool of the type employed in connection with loom tube frames in weaving having a surrounding sag-preventing flange between its ends for cooperation with a suitable support when the spool is in feeding position.

11. The combination with a tube frame, of a yarn spool supported at its ends on the frame, a flange on the spool between the ends thereof having an inner annular surface,

and a device on the tube frame for cooperating with said surface.

12. The combination with a tube frame, of a yarn spool supported at its ends on the frame, a flange projecting from the spool between the ends of the latter, and a pair of fingers carried by the tube frame and cooperating with opposite sides of the flange to hold the spool against sagging away from the tube frame.

13. The combination with a tube frame, of a yarn spool supported at its ends on the frame, a flange projecting from the spool between the ends of the latter, and a pair of fingers carried by the tube frame and cooperating with opposite sides of the flange to hold the spool against sagging away from the tube frame, and spring means acting on the fingers to hold them in cooperative relation to the flange.

14. The combination with a tube frame, of a yarn spool supported at its ends on the frame, a flange projecting from the spool between the ends of the latter, and a pair of fingers carried by the tube frame and cooperating with opposite sides of the flange to hold the spool against sagging away from the tube frame, and a single device for moving the fingers out of cooperation with the flange.
